UNITED STATES PATENT OFFICE

169,108

HAIRCUTTING GUIDE

Alex Sekerdy, Richmond, Va.

Application October 26, 1951, Serial No. 17,132

Term of patent 3½ years

(Cl. D86—10)

To all whom it may concern:

Be it known that I, Alex Sekerdy, a Polish national, who is a "displaced person" and at present without citizenship in any country, residing at 111 South Third Street, in the city of Richmond, State of Virginia, have invented a new, original, and ornamental Design for a Haircutting Guide, of which the following is a specification, reference being had to the accompanying drawing, forming a part hereof.

I claim:

The ornamental design for a haircutting guide, as shown.

ALEX SEKERDY.
